UNITED STATES PATENT OFFICE.

CLIFFORD C. BROWN, OF CARTERSVILLE, GEORGIA.

TENSION MECHANISM FOR SPOOLERS.

Application filed May 1, 1923. Serial No. 635,855.

To all whom it may concern:

Be it known that I, CLIFFORD C. BROWN, a citizen of the United States, residing at Cartersville, in the county of Bartow and State of Georgia, have invented certain new and useful Improvements in Tension Mechanism for Spoolers; and I do hereby declare the following to be a full, clear, and exact description of the invention, such as will enable others skilled in the art to which it appertains to make and use the same.

This invention relates to improvements in tension devices for spoolers, and more particularly to the type providing for the end-wise discharge of yarn from a bobbin.

The general object in view is the facilitating of the transfer of yarn from bobbins to spools while insuring against the delivery to the spool of any slubs or gouts with the yarn; and a more detail object is the accomplishment of this result by apparatus of increased capacity for speed and increased facility for access to moving parts.

A still further object is the construction of such a tension device in a manner enabling its application to the traverse of a spool winding machine either in the form of a single bar or a series of sections so constructed that when the traverse is once set it will not require resetting.

With these and further objects in view as will in part hereinafter become apparent and in part be stated, the invention comprises certain novel constructions, combinations and arrangements of parts as subsequently specified and claimed.

In the accompanying drawings,—

Figure 1 is a fragmentary sectional elevation through parts of a spooler supplied with an embodiment of the present invention, parts being broken away.

Figure 2 is a front elevation of the parts seen in Figure 1.

Figure 3 is a plan view thereof, parts being omitted.

Figure 4 is a sectional plan of one of the tension mechanisms, the section being taken through the upright of the bracket, and parts being broken away, the parts being seen on an enlarged scale.

Figure 5 is an elevation of the friction disc and pin of one of the tension mechanisms detached, part of the disc being broken away and seen in section.

Referring to the drawings by numerals, 1 is the spool-carrying spindle provided with

the usual grooved driving pulley 2 engaged and actuated by the cable 3 in the usual manner from a source of power not illustrated. There are as many of the spindles 1 as there are spools to be wound, each spool being mounted, as seen at 4, on the upper portion of the spindle. Outward or in front of the line of spools 4 is arranged a rail or bar 5 which may be a continuous bar extending throughout the length of the machine in front of all of the spools or may be made in sections as preferred. Whether made in one piece or in sections, the bar 5 is connected by arms 6 to the builder motion of the machine, not shown, whereby the bar 5 is caused to travel up and down in the well known fashion of builder motions and the traverse thereof is adjusted according to the thickness of the yarn and speed of the spools so as to build yarn fed across the bar 5 onto the several spools 4. Beneath the bar 5 and slightly outward therefrom is a rail 7 which is provided with a series of upstanding studs 8, each relatively short and each adapted to sustain a bobbin such as indicated at 9, the location of the rail 7 being such as to cause the axis of the bobbin to extend in a line approximately flush with the outer edge of the bar 5. There are as many studs 8 as spindles 1, and for each stud 8 there is provided on the bar 5 a tension mechanism to receive and guide the yarn from the respective bobbin 9. As each of these tension mechanisms is a duplicate of all the rest, only one will be described in detail and that description will be applicable to all. It is important to note that each of the tension mechanisms, as clearly seen in Figure 3, while arranged immediately above the respective bobbin 9 is disposed laterally of the space between two of the spools 4 so that yarn passing from the bobbin 9 through the given tension mechanism passes on an incline, which for the sake of convenience will be called rearward, to the spool 4 to which it is being fed.

Each of the said tension mechanisms consists of a disc 10 mounted on the upper surface of the bar 5 and provided with restraining means, a yarn approach, and means for clearing foreign substances. The disc 10 is centrally apertured and a pin 11 snugly fits in the aperture of the disc and is provided with a head for enabling the pin to be suspended through the disc with the head resting on its upper surface. The bar 5 is pro-

vided with a longitudinal slot 12 of a width approximately equal to the diameter of the pin 11 and permitting the pin to extend freely therethrough while allowing lateral movement of the pin therein and yet providing a comparatively snug fit for the pin. Considering the direction of the incline of the yarn toward the spool onto which it is being fed from its respective tension mechanism as rearward, the slot 12 extends forwardly from the normal operative position of pin 11 and opens into a laterally-extended aperture or recess 13 formed through the plate 5 for enabling discharge of slubs, gouts and other foreign matter. A bracket plate 14 is fixed to the bar 5 and overhangs the disc 10 and pin 11 at a distance above the disc less than the length of the pin 11, so that the pin and disc cannot escape from bar 5 while bracket 14 remains in place. The bracket 14 is preferably detachably held as by screws or bolts 15, 15, engaging the bracket and the bar 5, so that the bracket may be detached for enabling renewals or replacements as required. A yarn feeding slot 16 opens through the outer edge of the bar 5 and extends inward to a point flush with the edge or periphery of disc 10 when the pin 11 is in its normal position at the rear end of slot 12. A set screw 17 extends through the bracket 14 at a point above the disc 10 and preferably in position for having the screw engage the disc as seen in Figure 4 with the outer portion of the screw flush with the periphery of the disc. A lock nut 18 is preferably mounted on the screw 17 so that the screw may be effectively retained at any given adjusted position, and, in operation, the best results are obtained after the yarn has been threaded into place by screwing the set screw 17 down against the disc 10 until it ceases to revolve, and then backing the screw off just far enough to allow the disc to revolve freely. The lock nut 18 is then tightened and the parts are held in this position for continued operation. Thus the disc 10 is not permitted to move upward away from bar 5 a distance greater than the thickness of the yarn being fed, whereby all slubs, gouts, and other foreign substances are removed and assurance is given that the thread wound on the spool will be clean and clear, free from kinks, lint or other objectionable condition.

The disc 10 has the angle between its under face and its periphery slightly rounded off, as seen at 19, which obviates danger of undue cutting of yarn and facilitates threading of the same into place. It will be noted also that the slot 16 at its outer terminus is slightly enlarged by having its walls beveled or rounded outward, as seen in Figure 4, so as to facilitate introduction of yarn without danger of injury thereto.

In operation, it is customary to have a

small quantity of yarn already on the spool which is mounted on the spindle 1. The operator grasps the yarn from the spool and drawing it across and above the bar 5 ties it to the yarn from the bobbin 9. He then drops the yarn across the bar 5 in front of the tension mechanism and the yarn immediately threads itself into place by dropping into the slot 16 and moving under disc 10 until it contacts with pin 11 where it continues to feed to the spool. This automatic threading of the yarn is incident to the pull of the spool on the yarn from the bobbin at an incline relative to the tension mechanism, which pull results in the ballooning of the yarn as it comes off of the bobbin, unwinding therefrom clockwise.

It is to be noted that the studs 8 are relatively short and of a thickness equal approximately to the diameter of the bore of the bobbin 9, so that the bobbin may rest on rail 7 and be held thereon while the yarn is being drawn upward or longitudinally of the bobbin off of the same. The studs 8 are formed short for the purpose of saving vertical space or head room for facilitating application and removal of the bobbins and for enabling more ready access to the pulleys 2 and the adjacent parts.

The disc 10 functions not only to tension the yarn and to remove large foreign articles, but also because of its revolving motion removes the specks on the yarn that frequently pass the knife type of catcher, and the location of the recess or aperture 13 is such that the revolving disc will continue to clear itself and discharge foreign substances down through the bar 5 so that there will be no accumulation, but if a large body of dirt or foreign matter, such as lint, should collect in contact with the disc, so as to interfere with its effective functioning, the revolving motion of the disc will either clear away such foreign substance or cause the disc and pin to move forwardly in the slot 12 until such collection is discharged. Immediately after such discharge, the parts will move back to their normal position. The location of the slot 16, and particularly its inner terminus, is important in that the angle presented by the slot immediately beneath the periphery of the disc 10 will insure the removal of gouts and slubs from the yarn by the co-operation of the moving edge of the disc with the stationary edge of the slot. In every instance, the slub or other objectionable matter will either be sheared off or the yarn will be broken. The relative location of each tension mechanism with respect to its spool causes the yarn to exert a constant pull on the pin 11 in a direction toward the rear end of the slot 12 so as to constantly maintain the pin and disc in proper operative position and to return the same to such position in the

event of such extraordinary action as above stated when a collection of foreign substances causes the pin to move forwardly in the slot for clearing the disc.

5. What I claim is:—

1. In spool winding mechanism, the combination, with a spool carrier, and a yarn supply carrier, of a tension device arranged laterally of the front of the spool carrier 10 for causing the yarn delivered from the yarn supply carrier and passing the tension device to extend angularly toward the spool carrier for exerting a stress on the tension device for normally maintaining the parts 15 thereof in operative relation.

2. In spool winding mechanism, the combination, with a spool carrier for a plurality of spools and a yarn supply carrier for a plurality of bobbins, of a tension device arranged substantially above each bobbin and in line with the space between spools for causing the yarn to approach each spool angularly thereof, each of the tension devices having a movable part retained normally 25 in operative position by the yarn being wound incident to the angular location of the yarn occasioned by the relative location of the parts.

3. A tension device for spool winding 30 mechanism comprising a slotted support, a disc revolvably mounted on the support, and a pin extending through the disc and through the slot, the disc being movable laterally in the direction of the length of and 35 relative to the slot.

4. A tension device for spool winding mechanism comprising a slotted support, a disc revolvably mounted on the support, a pin extending through the disc and through 40 the slot, and a bracket carried by the support and overhanging the disc and pin and spaced therefrom a distance less than the length of the pin.

5. A tension device for spool winding 45 mechanism comprising a support, a disc revolvably mounted thereon, a bracket fixed to the support and overhanging the disc, and a set screw carried by the bracket in position for engaging the upper surface of the disc.

50 6. A tension device for spool winding mechanism comprising a support, a disc revolvably mounted thereon, a bracket fixed to the support and overhanging the disc, and a set screw carried by the bracket in position 55 for engaging the upper surface of the disc substantially at the periphery thereof.

7. A tension device for spool winding mechanism comprising a support, a disc revolvably mounted thereon, a bracket overhanging the disc, and a set screw carried 60

by the bracket in position for engaging the upper surface of the disc, the support being formed with a yarn feeding slot leading to a point beneath the disc.

8. A tension device for spool winding 65 mechanism comprising a support, a disc revolvably mounted thereon, a bracket overhanging the disc, and a set screw carried by the bracket in position for engaging the upper surface of the disc at substantially 70 the periphery thereof, the support being formed with a yarn feeding slot extending beneath the disc.

9. A tension device for spool winding 75 mechanism comprising a support, a disc revolvably mounted thereon, a bracket overhanging the disc, and a set screw carried by the bracket in position for engaging the upper surface of the disc at substantially 80 the periphery thereof, the support being formed with a slot leading to and terminating beneath the periphery of the disc substantially in line with the set screw.

10. A tension device for spool winding 85 mechanism comprising a support having a longitudinal slot, a disc revolvably mounted on the support, a pin extending through the disc and the slot and movable along the slot, a bracket overhanging the disc and pin, and a set screw carried by the bracket 90 in position for limiting upward movement of the disc, the support being formed with a yarn feeding slot leading to and terminating beneath the disc.

11. A tension device for spool winding 95 mechanism comprising a support having a longitudinal slot, the support being also formed with a discharge opening for foreign substances, a disc revolvably mounted on the support, a pin extending through the disc 100 and the slot and movable along the slot toward said discharge opening, a bracket overhanging the disc and pin, and a set screw carried by the bracket in position for limiting upward movement of the disc. 105

12. A tension device for spool winding mechanism comprising a support having a slot opening into a discharge opening for foreign substances, a disc revolvably mounted on the support, and a pin extending through the disc and slot and movable in the slot 110 toward and away from the discharge opening.

In testimony whereof I affix my signature in presence of two witnesses.
